US0D1100885S

(12) **United States Design Patent** (10) **Patent No.:** **US D1,100,885 S**
(45) **Date of Patent:** **** Nov. 4, 2025**

(54) **WIRELESS EARBUD**

(71) Applicant: **HUAWEI TECHNOLOGIES CO., LTD.**, Guangdong (CN)

(72) Inventors: **Yangbin Xuan**, Shenzhen (CN); **Jie Huang**, Shanghai (CN)

(73) Assignee: **HUAWEI TECHNOLOGIES CO., LTD.**, Shenzhen (CN)

(**) Term: **15 Years**

(21) Appl. No.: **29/945,969**

(22) Filed: **Jun. 6, 2024**

Related U.S. Application Data

(62) Division of application No. 29/869,128, filed on Dec. 22, 2022, now Pat. No. Des. 1,035,626.

(57) **CLAIM**

The ornamental design for a wireless earbud, as shown and described.

DESCRIPTION

FIG. 1 is a front perspective view of a wireless earbud, showing our new design;

FIG. 2 is a front view thereof;

FIG. 3 is a back view thereof;

FIG. 4 is a top view thereof;

FIG. 5 is a bottom view thereof;

FIG. 6 is a right side view thereof;

FIG. 7 is a left side view thereof; and,

FIG. 8 is a back perspective view thereof.

The broken lines in drawings show portions of the wireless earbud that form no part of the claimed design.

1 Claim, 8 Drawing Sheets
